DIE FOR FORGING THE CUTTING FACES OF
ROCK DRILL BITS

Stephen Peter Humphrey, Max Meadows, Va.

Application October 7, 1943, Serial No. 505,395

2 Claims. (Cl. 76—5)

This invention relates to dies for forming or renewing the cutting faces of rock drill bits, particularly rock drills having four cutting edges radiating from a common axis.

One of the objects of the invention is to provide a two-part die assemblage, including four cutters which by a single reciprocatory relative movement of the dies in a press, are forced together from different directions through the bit stock, severing the same by cutting off the old working face, and forming a new face at the end of the stock.

Another object of the invention is to provide a pair of dies each carrying a cutter in fixed position relative thereto, which cutters are movable with the dies from opposite directions toward one another along a common line of symmetry to a position of point to point contact, and a pair of movable cutters carried by one die on opposite sides of its fixed cutter, swingable responsive to the action of a cam carried by the other die toward one another to a position of point to point contact with the fixed cutters.

Another object of the invention is to provide a die construction as described, in which the movable cutters are normally spring retracted in a position to straddle the bit stock upon the initial closing movement of the dies.

Other objects of the invention will appear as the following description of a preferred and practical embodiment thereof proceeds.

In the drawings:

Figure 1 is a front elevation showing the bit face forming dies of the subject invention, set up in a press in separated relation, part of the press being omitted;

Figure 2 is a vertical cross-section in a plane passing through the common axis of contact of the cutters, showing the dies in closed position;

Figure 3 is a cross-section through the dies in a plane perpendicular to the common axis of the cutters, the latter being in closed position;

Figure 4 is a section taken along the line 4—4 of Figure 3;

Figure 5 is a perspective view of the working end of a drill bit, showing the nature of the face which the dies of the subject invention are adapted to produce.

Before referring specifically to the drawings, it may be stated that there are a number of known ways of renewing the worn and scarified working ends of drill bits, including filling and pressing, some of which expedients are carried out by means of dies or sharpening machines, but all of which are inordinately time-consuming, and

at least for that reason, impractical; and that the present invention side-steps the shortcomings of the older methods by disregarding the old worn or chipped working face and forging an entirely new face adjacent thereto. This is done in a single and substantially instantaneous operation by cutting off the old face and producing a new face at the end of the bit stock.

Referring now in detail to the several figures, 10 a pair of cooperating die blocks 1 and 2 are provided, these being shown in Figure 1, set up in a conventional press 3, comprising a fixed platen 4 and a movable head 5 suitably actuated as, for example, by the pneumatically operated plunger 6.

15 The head is guided by guide rods 7, which are parallel to the direction of motion of the plunger, fixed to one of the die holding press members and slidable through guide apertures in the other.

The press has the lower and upper jaws 8 and 20 9, each formed with a buttress ledge 10, the confronting faces of which ledges lie in planes perpendicular to the direction of movement of the plunger, and provided with the respective clamping plates 12 and 13, which overhang the ledges 25 and are secured by the bolts 14.

The bases of the die blocks 1 and 2 are prismatic in shape, to seat firmly in the channels formed by the overhanging clamping plates, against the respective ledges. The width of the 30 bases of the die blocks is slightly greater than the width of said channels, so that the die blocks may be firmly clamped. The shape and size of the bases of the die blocks is immaterial to the invention, and may be varied to adapt the die blocks to any type of press. As shown, the die blocks are secured at one side in the press jaws 8 and 9, indicating that other dies for other purposes, with which the invention may not be concerned, may be kept set up in the press without 35 removing the die blocks 1 and 2.

Now, referring particularly to Figures 1, 2 and 3, the die blocks 1 and 2 are formed with intermediate recesses 15, extending from the front of the die blocks to a common plane intersecting 45 the die blocks intermediate their front and base faces and parallel to the base face. The said recesses are bounded by the side walls 16 and 17, back walls 18, and bottom walls 19, all of which are integral parts of the respective die blocks. 50 Fixed cutters 20 and 21 fit removably in the respective recesses, resting against the bottom walls 19 thereof, and being secured by the stud bolts 22. The inner ends of the fixed cutters are of tetrahedral shape, as shown, and symmetrical both as 55 to their faces and edges with respect to a common

line passing through their points parallel to the axis of the bit stock, and which line may be considered the axis of the dies.

One of the die blocks, for example, the die block 2, is provided with a pair of movable cutters 23 and 24, one on each side of the fixed cutter 21, swingable laterally in transverse slots 25 formed intermediately in the side wall portions 16 and 17 of the die block 2, and journaled on pivot pins 26 anchored in said side walls. The working ends also of the movable cutters are of tetrahedral shape, and the movable cutters are so shaped and dimensioned that when they have been swung to fully closed position, their points meet the points of the fixed cutters at a common point in the axis of the die, while their cutting edges which lie in a plane intermediate the inner and outer faces of the cutters perpendicular to the axis of the die, coincide linearly throughout their length, this being the position of the cutters when complete severance of the bit stock and forging of the new working face have been accomplished.

The other die block, for example, the die block 1, is provided with cams 27 so situated on opposite sides of the fixed cutter 20 as to be contacted by the movable cutters upon the approach of the die blocks, and so shaped as to guide said movable cutters inwardly at a uniform rate of travel until they have reached closed position of contact with respect to the fixed guide members.

The movable cutters 23 and 24 are normally held in retracted position by springs 28, so that they are able to straddle the bit stock in the initial relative approach movement of the die blocks until the movable cutters are engaged by the cams 27.

In operation, the bit, which is to be re-faced, is first heated to the proper forging condition, then positioned adjacent its end between the open dies with its axis approximately in coincidence with the axis of the die, which is indicated by the point X in Figure 1. The press is then actuated to bring the dies together, forcibly closing the cutters through the bit stock, severing the terminal portion with the old working face, and simultaneously forging a new working face. The slight swell in the diameter of the bit stock incident to the displacement of metal by the cutters is no detriment to a tool of this nature. The cutting face produced by the subject die tool is illustrated at 29 in Figure 5.

The bit is then re-tempered in usual manner, and is ready for use.

While I have in the above description disclosed what I believe to be a preferred and practical embodiment of the invention, it will be understood to those skilled in the art that the details 5 of construction and arrangement of parts, as shown and described, are by way of illustration and not to be construed as limiting the scope of the invention as defined in the appended claims.

What I claim as my invention is:

- 10 1. Die tool for forging cutting faces on drill bits comprising a pair of cooperating die blocks adapted to be brought together in a press, a pair of similar cutters having tetrahedral cutting ends pivotally mounted in spaced relation on one block 15 to swing into point to point contact, springs thrusting between said cutter and blocks to normally hold said cutters in retracted position, the other block having a pair of similar cams engageable by said cutters for causing them to 20 move together responsive to the relative approach movement of said blocks, and a pair of cutters, fixed one with respect to each block having tetrahedral cutting faces similar to the cutting faces of said movable cutters positioned to 25 be moved into point to point contact with one another and with the points of said movable cutters and with cutting edges in linear contact in a common plane intermediate the inner and outer faces of said cutters, the faces and edges 30 of the cutting ends of all of said cutters being symmetrical with respect to said plane and with respect to a line perpendicular to said plane passing through the common meeting point of the points of said cutters.
- 35 2. Die tool for forging cutting faces on drill bits comprising a pair of cooperating die blocks adapted to be brought together in a press, a pair of similar cutters having tetrahedral cutting ends 40 pivotally mounted in spaced relation on one block to swing into point to point contact, springs thrusting between said cutter and blocks to normally hold said cutters in retracted position, the other block having a pair of similar cams engageable by said cutters for causing them to 45 move together responsive to the relative approach movement of said blocks, and a pair of cutters, fixed one with respect to each block having tetrahedral cutting faces similar to the cutting faces 50 of said movable cutters positioned to be moved into point to point contact with one another and with the points of said movable cutters and with cutting edges in linear contact.
